(No Model.)

LA VERNE W. NOYES.

GRAIN HARVESTER.

No. 358,063.

Patented Feb. 22, 1887.

UNITED STATES PATENT OFFICE.

LA VERNE W. NOYES, OF CHICAGO, ILLINOIS.

GRAIN-HARVESTER.

SPECIFICATION forming part of Letters Patent No. 358,063, dated February 22, 1887.

Application filed December 28, 1885. Serial No. 186,924. (No model.)

To all whom it may concern:

Be it known that I, LA VERNE W. NOYES, a citizen of the United States, residing at Chicago, in the county of Cook and State of Illinois, have invented certain new and useful 5 Improvements in Grain-Harvesters, which are fully set forth in the following specification:

This invention relates to the platform-adjusting devices of a harvester, and comprises 10 mechanism for raising and lowering and mechanism for tilting.

In the drawings, Figure 1 is an inner front perspective of the drive-wheel and frame and a portion of the front sill of the platform, 15 showing the adjusting mechanism which constitutes my invention. Fig. 2 is an outer side detail elevation of the tilt-adjusting lever and its connections.

A is the drive-wheel.

20 B is the wheel-frame. C is the main frame. These two frames, which are adapted by means hereinafter described to be locked rigidly together, constitute the harvester-frame, which is supported on and adapted to be tilted over 25 the drive-wheel axle. The wheel-frame is substantially a cranked shaft, having the drive-wheel A journaled on the wrist B' and the main frame C pivoted on the parallel wrist B'', said wrists being on opposite sides of the connecting crank-arm B³. Rigid, and preferably 30 integral, as illustrated, with the arm B³ of the wheel-frame B is formed the segment-rack B⁴, having its upper end braced by the radial arm B⁵, also integral with the arm B³.

35 The main frame C comprises the platform-sill C' and the bracket C², secured upon said sill. Said bracket comprises the arm C²¹, which extends to and is pivoted on the wrist B² of the wheel-frame B, and the upright 40 curved arm C²², which stands up alongside of the segment B⁴ and is recessed to fit and receive the same, striding and clasping its curved edge. Said upright curved arm C²² has near its upper end two bearings, c²² c²², in 45 which is journaled the upright shaft D, and between which there is fixed on said shaft the endless screw or worm D', which meshes with the rack B⁴. Said shaft D has a crank-handle, D², at its upper end, by means of which 50 it may be rotated.

The tongue E is pivoted to the wheel-frame,

preferably at the wrist B², as illustrated. It is provided with the bracket e, secured to it on the under side, and thereon, at e', is pivoted the lever E', having at the upper end the 55 notched segment E¹⁰. To said lever, at the center e² of said notched segment, is pivoted the lever E², and between the pivots e' and e² there is connected the link E³, which has the other end pivoted to the lower part of the 60 main frame C, as at c, on the platform-sill C'. For stiffness said link has rigid with it the brace E³⁰, extended obliquely inward from the point e³ and connected to the pivot c' on the sill C' in line with the pivot c. 65

The draft-chain F is secured to the extension b⁴ at the upper end of rack B⁴, and is also secured upon the stud e²⁰, jutting from the inner side of the lever E², and extends thence forward for the purpose of being connected to 70 the driving-power. To the outer side of the lever E² the slide-bar E²¹ is retained by means of the stud e²¹, passing through the slot e²¹⁰ in said slide-bar and having its head overlapping the edges of the slot. The lever E² has 75 also the projection e²² near its upper end, pierced to receive the rounded end E²¹⁰ of the slide-bar E²¹, and around said rounded end and under the projection e²² is coiled the spring E²². The lower end of the slide-bar E²¹ is formed as 80 a tooth, E²¹¹, adapted to engage the notches of the notched segment E¹⁰, and the spring E²² tends to force said tooth into such engagement. Both the lever E² and the slide-bar E²¹ are provided at the upper end with the horizontal handles E²³ and E²¹³, respectively, the former overhanging the latter and only a short 85 distance above it, so that both may be grasped at once by the hand.

The raising and lowering of the machine is 90 effected by the screw D', rotated by the shaft D by means of the crank-handle D², said screw engaging the rack B⁴ and rocking the frame, of which the said arm C²², having the bearings of said screw-shaft D, forms a part, over its 95 pivot, the wrist B² of the frame B. The main frame being connected by the link E³ and lever E² to the tongue E, and the tongue being connected to the wheel-frame B at the pivot of said frame to the frame C, the raising or lowering of the main frame by rocking it over 100 said pivot causes the pole to rock said wheel-

frame over the wrist B', which is journaled in the drive-wheel. Both rocking motions being in the same direction—*i. e.*, either both upward or both downward—it is evident that if the tongue were lifted or lowered bodily by the movement of the main frame the tilt of the machine would not be at all affected by the raising and lowering; but, instead of being so lifted or lowered, the tongue has one fixed point, its bearing in the neck-yoke. The effect, therefore, of the vertical adjustment by the means above described would be to swing the machine up or down through an arc whose center is the bearing of the tongue in the neck-yoke. Such movement would slightly change the "tilt" of the machine but for the automatic correction, which will be now described. Raising the machine tends to tilt it forward or down, and lowering it tends to tilt it backward or up; but raising the machine throws the extension b⁴ forward, and the draft being upon the chain F, the forward movement of the extension b⁴ causes or allows the levers E' and E², secured together by the engagement of the tooth E²¹ in the notched segment E¹⁰ and moving as one piece, to rock forward over the pivot e'. Such forward motion causes the link E³ to draw forward and upward the lower front edge of the frame C—viz., the front sill, C—that is, to tilt the machine up. Similarly the lowering of the machine, which tends directly to tilt it up, operates, by means of the connection described, to correct said tendency and tilt it down an equal amount, so that, practically, no change of tilt is caused by the raising and lowering. The entire harvester-frame, comprising the wheel-frame and the main frame, locked in any desired relation by the engagement of the screw D' in the rack B', may be tilted, as desired, independently of the raising and lowering, by means of the lever E². Both handles E²³ and E²¹³ being grasped, and the slide-bar E²¹ pulled up to release its tooth E²¹ from the segment E¹⁰, the lever E³ being rocked forward over its pivot e', the stud e²⁰, passing through the draft-chain F, becomes the actual pivot of its motion, and joint at e' moves rearward, the lever E' rocking over its pivot e' on the bracket e and letting back the link E³, and the machine is tilted down or forward. Rocking the lever E² backward reverses all the above-described movements and tilts the machine upward or backward.

It will be seen that the levers E' and E² operate as a single-jointed lever, acting as one lever when the tooth and segment are engaged.

The general construction of the frames and the connection of the frames together, and of the tongue to the said frames, and of the draft-chain to the wheel-frame are shown and claimed in my application for patent filed June 29, 1885, Serial No. 170,141; and I do not herein claim anything except the modifications of the structure from that therein shown, which are the construction of the screw having its shaft journaled in the main frame and meshing with the rack on the wheel-frame, as the means of raising and lowering, and the construction of the jointed lever E' E², as the means for tilting; and in respect to these features

I claim—

1. In combination, substantially as herein-before set forth, the drive-wheel, the wheel-frame pivoted at the center of the wheel, the main frame pivoted to the wheel-frame eccentrically to the wheel and adjustably secured rigid with the wheel-frame, the tongue pivoted to the main frame, the jointed lever pivoted to the pole and connected from one side of the joint to the main frame and from the other side of the joint to the wheel-frame, and means for adjustably securing said jointed lever rigid at said joint. 85

2. In combination, substantially as set forth, the harvester-frame comprising both the bearings of the drive-wheel and the support for the cutting mechanism and pivoted at the center of the drive-wheel, the tongue hinged to the frame, the jointed lever pivoted to the pole and connected from one of its members to the frame at a point lower than the drive-wheel axle and from the other member to a point on the frame higher than the axle, and means for adjustably securing said jointed lever rigid at said joint. 90

3. In combination, substantially as and for the purpose set forth, the lever E', pivoted to the tongue and having the notched segment E¹⁰, the lever E², pivoted to the lever E' at the center of said segment, the links connecting said levers, respectively, with the harvester-frame, and the locking slide-bar E²¹, adapted to engage the notches of the segment. 100

In testimony whereof I have hereunto set my hand, in the presence of two witnesses, at Chicago, Illinois, this 23d day of December, A. D. 1885.

LA VERNE W. NOYES.
